UNITED STATES PATENT OFFICE.

WILLIAM KAYLOR, OF MUSKOGEE, OKLAHOMA, ASSIGNOR OF ONE-HALF TO J. L. KIMMEL, OF MUSKOGEE, OKLAHOMA.

ONE-PIECE RATCHET-WRENCH.

1,341,178.

Specification of Letters Patent. Patented May 25, 1920.

Application filed April 1, 1919. Serial No. 286,745.

To all whom it may concern:

Be it known that I, WILLIAM KAYLOR, a citizen of the United States, residing at 1116 Houston street, Muskogee, in the county of 5 Muskogee and State of Oklahoma, have invented a new and useful One-Piece Ratchet-Wrench, of which the following is a specification.

My invention relates to improvements in 10 open end wrenches and its object is to provide an extremely simple and inexpensive, yet a highly efficient and reliable wrench which may be constructed of one piece of metal and at the same time operate as a 15 ratchet wrench, being capable of turning a nut on one stroke and turning freely on said nut during its return movement.

With the foregoing in view, the invention resides in the specific construction of the 20 wrench hereinafter described and claimed, the descriptive matter being supplemented by the accompanying drawing.

Figure 1 illustrates a side elevation of a 25 wrench constructed in accordance with my invention, showing its relation with a nut on its working stroke.

Fig. 2 is a view similar to Fig. 1 illustrating the manner in which the wrench releases the nut on its return strokes.

In constructing the wrench, the usual 30 shank or handle 1 is provided on one or both ends with a head 2. Two of these heads are shown but since the constructions of both are the same, only one will be described.

A nut receiving notch 3 is formed in the head 2 and is provided with a substantially 35 central flat face 4 for contact with one facet of a hexagonal nut such as 5. The portions 40 of the head at opposite ends of the face 4, form two jaws 6 and 7 which I have termed a leading jaw and a following jaw respectively, since the former moves ahead of the latter during the working strokes of the

wrench. The following jaw 7 is provided 45 with a flat inner face 8 for contact with another facet of the nut 5, with a short face 9 to bind against the next facet, and with a rounded front end 10 which merges into said short face 9. The leading jaw 6 is provided with a flat inner face 11 for contact with one facet of the nut, and with a flat outer face 12 disposed at an obtuse angle to said face 11, said angle being greater than that existing between two adjacent 50 facets of the nut. This angular relation permits the wrench, on its return strokes, to rock freely upon the rounded jaw end 10 as a fulcrum, (see Fig. 2). By rocking the wrench in this manner and at the same time 55 holding it against the nut, it will take another hold of the latter, thus allowing the device to be used in the same manner as a ratchet wrench, which produces a great saving in time over the ordinary open end 60 wrench which must be alternately removed 65 from and applied to the nut.

I claim:

An open end wrench comprising a head 70 having a nut receiving notch provided with a substantially central flat face for contact with one facet of a hexagonal nut, the portions 75 of the head at opposite ends of said face forming a leading jaw and a following jaw; said following jaw having an inner flat face for contact with another facet of the nut, a short outer face to bind against the next facet of the nut, and a rounded front end merging into said short face and providing a fulcrum upon which the wrench 80 rocks on its return strokes; said leading jaw having an inner flat face to contact with the nut facet opposite said short face, and an outer flat face at an angle to said inner face greater than the angle between two nut 85 facets, permitting rocking of the wrench upon the aforesaid fulcrum.

WILLIAM KAYLOR,
